REBECCA WEAVER, OF WASHINGTON, DISTRICT OF COLUMBIA.

Letters Patent No. 77,423, dated April 28, 1868.

IMPROVEMENT IN TRUNKS.

The Schedule referred to in these Letters Patent and making part of the same.

Be it known that I, REBECCA WEAVER, of the city of Washington, in the District of Columbia, have invented a new and useful Cylindrical or Rolling Trunk; and the following is a full, clear, and exact description of the same, reference being had to the accompanying drawings, making a part of this specification, in which—

Figure 1 represents a vertical section, showing the cylindrical and longitudinal ribs, to which the compartments are to be attached when required.

Figures 2 and 3 show the jack-up cleats, to support the tills; also for dividing the packing-space into any desired number of sections.

Figure 4 shows a perspective view of the compressible or collapsing tills braced up.

Figure 5 is a view of the same, with the braces folded down, so that the till collapses perfectly flat, and can be placed, along with the jack-up cleats, (which fold up like a jack-knife,) in either end of the trunk, thus leaving an uninterrupted cylinder.

Figure 6 shows one form of lid, with situation of a central lock, throwing two, three, or more radiating bolts, and also the cap for protecting the lock thrown back to admit the key.

Figure 7 shows an enlarged perspective view of the central cap, which protects this lock, and the staples and chains for securing it.

Figure 8 shows a perspective view of the cylindrical trunk, with the lid in the end made to open from the circumference, the semicircular halves folding together upon a diametrical hinge, allowing half the lid or top to be lifted without unfastening the opposite half; or, when required, the whole is easily removable, to accommodate the passage of the tills.

Figure 9 represents an under side view of the folding lid, with hinge-bolts, transverse bolt, and opposite lock, of common make.

Figure 10 is a cross-section of overlapping cap, of corrugated rubber, leather, canvas, or other material, looking to protection of the ends of the trunk when in a horizontal position, exposed to hard knocks. When this cap is used, the heavy end-roller or band is set back, so as to present a very narrow metallic rim, provided with staples, over which the openings in rim of the cap fall, and through which a small, strong chain will run, fastening with padlock.

Figure 11 represents one mode of constructing the interior of the cylindrical or rolling trunk, providing for two drawers, playing longitudinally on grooves, and locked on the cross-piece, or fastened by jack-up cleats under lid.

Figure 12 gives a diminutive view of the drawer or wardrobe-trunk, with drawers closed, and locked on cross-piece, like a bureau.

Figure 13 is a view of bachelor's box, or small-size trunk, presenting one cylindrical drawer, with lid raised.

The object of my invention is to protect the travelling-community from the exposure, damage, and loss of their baggage, by the breaking open and smashing up of trunks, incident to the rough handling of porters, baggage-masters, expressmen, &c., and to provide the means by which heavy or bulky luggage can be handled and transferred with greater facility and safety. As the constant practice of "baggage-smashers" is to end up and roll over and over the oblong and angular trunks now in vogue, wrenching off hinges, locks, &c., I propose to introduce an article which invites, or is uninjured by, such handling, or which can, if in a horizontal position, be readily moved by a touch of the foot.

My invention consists in the construction of cylindrical or rolling trunks, made of such material and secured together in such a manner as to enable them to endure very great pressure from the exterior, also being water-proof. The interior is provided with specially-adapted tills, and adjustable fixtures to hold them in place, so that any desired number of compartments may be had, or the entire space left in one.

To enable others to make and use my invention, I will describe it more in detail, and according to letters of reference marked on the drawings.

The cylindrical body A may be made of any desired diameter and length, and of any material suitable for the purpose, such as sheet steel, galvanized iron, or other metal, wood, pasteboard, leather, or India-rubber. The ends are protected by securing metallic bands, a' a', both on the inside and outside of the body A, and also circular bands, I I I, at suitable intervals in space between the ends; also longitudinal ribs, b b, are secured to the inner portion of the cylinder. These ribs and bands may be of any required number, so as to form a frame or skeleton of sufficient strength, simply calling for an outer covering of consistent quality.

When made of material less tenacious than metal, the longitudinal ribs b b may be provided with overlying circular bands of flat thin metal, to be riveted where they intersect, forming a sort of lattice.

The longitudinal ribs b b here show a series of interstices or notches, e e, at intervals, into which the jack-up cleats C are placed, to support the tills B B in a fixed position, when it is desirable to have separate compartments. The tills are constructed of ordinary material used for such purposes, having a bottom, B' B', and two rims, d d, to which, or between which, cloth or leather is attached. They are also provided with hinged props, f f f, to hold the rims d d apart when in use; and, when not needed for separate compartments, the props f f f fold down on the bottom, B', and the tills collapse, and can be packed snugly in one end of the cylinder. The cleats C will also jack up, and take but little room in the packing-space.

The lid or cover D is provided with India-rubber packing, e e, in the edge, so as to fit in the recess in the rim e' e', and secure it water-tight. The lid or cover D is secured by a lock in the centre, having three or more bolts, g g g, which catch under the ledge inside of the rim e' e'.

The lock and key-hole are protected from dust, meddlers, or other encroachments, by a rim, h, projecting upward, with an elastic packing on its edge, and a metallic flanged cap, E, to fit on over it.

Openings, i i i, occur all round the flange j, and a series of staples, k k k, in corresponding situations on the lid below, is barely large enough to admit the play of a very small chain, l, so that the cap E, falling forward, is neatly secured by a miniature padlock, m. Thus, when the lid is put in and locked, and the cap is put on the trunk is made water-tight, and is doubly secured from being opened.

There are various ways that the opening end may be covered securely. A lid may be in two parts, working by means of a diametrical hinge, G G, admitting of one-half being opened at a time, or the whole lifted out, to allow the passage of the tills. When closed, this lid is mainly secured by sliding bolts on the inside, and lock near edge.

There are various ways in which the interior arrangements of the cylindrical or rolling trunk may be constructed, one modification being shown in fig. 11, a cylinder, H, cut in two longitudinally, each section forming a drawer or cleats, so as to be drawn out of the main or outward cylinder A, each section being provided with a lid, and as many compartments as desirable, so that whatever is packed in one of the compartments does not come in contact with any of the others, and may be conveyed in good order, though other compartments remain empty, these jack-up cleats, or other suitable braces, providing for any mode of distribution in packing.

The last-described trunk may be properly designated the wardrobe-trunk, affording, as it does, admirable facility for packing away, and conveying, without injury, long and rich draperies and robes. When locked, no trunk can be more safe from being crushed or broken open, it forming a double cylinder.

The cylindrical figure first described, with its appendages, as shown in the several figures, 1 to 7, is designed for general utility, and may be made of such form and size as will be convenient for all the purposes of a journey, from the capacity of the largest "Saratoga" down to a bachelor's box or hand-valise, or even a travelling-satchel. They are all designed to be made water-tight, so that the contents can be saved if the trunk is cast into the water, and will serve admirably as life-preservers, singly, or, if lashed together, will form a buoyant raft, in cases of shipwreck or loss of vessels by fire at sea.

It will be readily seen that there are many and great advantages to be derived from this improved mode of constructing travelling-trunks, among which the following are prominent:

First. It is a well-known fact that there is no way in which a given weight or amount of material possesses so much strength as it does in cylindrical form. Hence, a cylindrical trunk, of the same weight of another of the ordinary form, will endure nearly or quite double the pressure on the outside without crushing; and, for the purpose of fitting a lid or cover water-tight, the cylindrical form presents the best, surest, and easiest.

Second. For the convenience of handling, the cylinder is much more desirable than the sharp, angular box. It can be carried on the shoulder by means of a grieve on the heavy end-rollers, and loaded on or unloaded from a wagon by rolling along an inclined plane, readily applied.

Third. A heavy trunk of this kind can be easily moved anywhere on a plane, from one side of a room to another, without injury to fine carpets, as is now frequently done in the hurry and bustle of hotel-porters, the heavy rims on the ends serving the purpose of wheels to roll on; and these rims further serve to elevate the body of the trunk from the floor, or, in case of out-door exposure, from the wet ground or other filthy foundations in depots, &c., &c.

There may be two or more bands or rollers, similar to the end-rims I I I I, placed, at suitable intervals, on the body A of the trunk, so that, whatever the material used in forming the body, the inside bands or hoops a' a' and ribs b b, and the outside bands or rollers, will give it a sufficient support against all smashing.

Having thus fully described my invention, what I claim as new, and desire to secure by Letters Patent, is—

1. A rolling-trunk, constructed as herein described, as and for the purposes specified.
2. I claim the construction of the tills B B, having rims d d, with hinged or other props f f, so that they may be set up or collapsed at pleasure.

3. I claim the jack-up cleats C, in combination with the tills B and the cylindrical or rolling trunk A, substantially as and for the purposes herein set forth.

4. I claim the manner of constructing the cover or lid D and cap E, for protecting the lock, and securing the trunk water-tight, substantially as herein set forth.
5. I claim the manner of constructing the folding cover or lid K K with the hinged bolts and overlapping cap, substantially as and for the purposes herein set forth.
6. I claim placing drawers H within the cylinder A, to be drawn out at the end, thus giving double security to the contents when closed, as herein described.

REBECCA WEAVER.
